UNITED STATES PATENT OFFICE

FREDERICK H. LUENSE, OF CHICAGO, ILLINOIS, ASSIGNOR TO ROTOSPRAY MANUFACTURING CO., OF CHICAGO, ILLINOIS, A CORPORATION OF ILLINOIS

ROTARY SPRAYING SEPARATOR

Application filed December 3, 1925. Serial No. 72,993.

My invention relates to separators and has to do more particularly with the provision of a rotary spraying separator for the separation of fluids and solids, and is particularly useful in connection with paints such as wall paper paints, although not confined thereto.

In the manufacture of paints for making wall paper, and for that matter also in other kinds of paints, the various ingredients that go into the manufacture of the same are not always dissolved and it is desirable to eliminate, remove or strain such solids from the fluids.

One of the objects of my invention is to provide a rotary spraying separator of the character described which is simple in construction, comparatively cheap to manufacture, easy to maintain and clean, and positive in its operation. There are various features and advantages which will be pointed out herein or will be apparent from an understanding of the machine.

For a better understanding of my invention reference is to be had to the accompanying drawings, in which—

Fig. 1 is a side elevation partly in section;

Fig. 2 is a top plan view of Fig. 1; and

Fig. 3 is a top view of the rotary sprayer head along the line 3—3 of Fig. 1.

Referring first in general to the operation of the machine, the paint is fed to the machine through a pipe or feed chute so that it runs down into the upper feeding funnel and into the rotating spraying pans carried at the lower end of the motor shaft. The paint feeds down into the pans and is thrown outwardly by centrifugal force against a separator or straining screen. Some of the fluid of this sprayed paint is forced through the screen and the solids and some of the fluid runs downwardly into the lower pan, which after it fills up comes in contact with the surface of the spraying cone at the bottom of the shaft which acts also as a centrifugal pump, gradually working upwardly to be again thrown against the screen to be strained; this operation continuing in a cycle until the lower pan is filled with solids, when it is removed and cleaned.

Referring now more in detail to the pre-

ferred form of my machine as illustrated herein, I provide a suitable driving motor 8 mounted in a tripod or supporting frame consisting of three arms 9 which meet at the top and have a suspending eye 10 attached thereto so that the machine may be suspended from above if desired, or it may be set on the floor. A motor shaft 11 extends downwardly and supports the spraying mechanism which includes a plurality of spraying discs preferably bowl shaped elements 12 secured together by bolts 13 which pass through the rims of the pans and through separating sleeves 14. I preferably employ the bowl shape as this gives greater friction to the material than if a flat disc were used, and thus greater force to the sprayed material. All pans above the lower one are open at the bottom at 12° so that the paint will feed on downwardly through the multiple bank of pans. The lower pan 12° is preferably continuous, that is without an opening in the bottom, and carries a hub 15 for securing the spraying device to the shaft 11. I have shown three pans, but it is to be understood that the number of pans may be varied to meet the conditions of use and the output desired. That is, by using a greater number of pans a greater output may be secured.

Beneath the lowermost pan I attach a combination pump and spraying cone 16 preferably open at the bottom and extending downwardly so that the overflow or surplus paint going into the bottom pan 29 will come in contact with this cone. By reason of the shape of the cone and its rotary motion this surplus paint is again drawn upwardly to be sprayed against the straining screen. Thus the spraying and pumping actions are continuous so long as any fluid matter remains to be strained.

Above the spraying pans I provide a combined cover and feeding pan 17 held in an outer rim 18, which rim rests in the casing 25 so that this pan may be lifted upwardly for access to the interior of the machine. In order to hold the pan clear of the interior I provide yielding holding elements in the form of flat springs 19 secured to the arms 9 of the frame, so that the rim 18 may be forced

up over the springs 19 and held there. To drop the feeding pan 17 a spring 19 is pushed outwardly to release the pan so that it may be lowered into feeding position.

5 The paint may be fed to this pan 17 in any suitable way and I have shown a feed pipe 20 with its nozzle positioned above the pan and which pipe may be so arranged that it can be turned to one side to allow the feeding pan 17 to be raised.

10 A suitable straining screen 21 is provided, being fastened by rings 22-23 at its upper and lower edges to tapered or angular rims 25'-26'. This screen 21 is readily removable 15 from its upper and lower support by removing the wedging rings 22-23, so that it may be taken off of the machine for cleaning or to be replaced by a screen of different size to suit the particular work.

20 The protective outside casing 25 which carries rim 25' is suspended from the legs 9, being attached by clamping screws 24 which extend through slots cut into the side of the feet of legs 9 so that it may be removed with 25 the screen for cleaning or permit access to the rotary spray. To remove casing 25 and attached screen, or to lift the frame 9 and the spray mechanism, it is only necessary to give a half turn or so to screws and then rotate 30 the legs so the slots clear the screws and then the parts may be separated.

Extending downwardly from the casing 25 is a circular or annular pan 26 which extends around the machine, being removably 35 clamped to the casing 25 at 27. This annular pan 26 extends upwardly with a rim 26' to which, as stated, is fastened the lower end of the screen 21. Thus the fluid paint which is forced through and strained by the screen 21 40 flows downwardly into this pan, from which it flows out through the nozzle 27.

A number of legs 28 are fastened beneath the pan 26 on which to rest the machine on the floor and protect the cone 16, when the 45 lower pan 29 is off.

In order to take care of the surplus or overflow paint which is not forced through the straining screen 21 and runs down the inside, and to collect or receive the solids which are 50 strained from the fluid by the screen, and to permit a continuous or successive straining operation upon the paint until finally solids only are left, I provide a lower drip or receiving pan 29 which is removably suspended 55 from or attached to the machine by an annular rim 30 having three clearance notches 31 so that the pan may be rotated or turned until the clearance notches 31 are opposite the extensions 32 on the legs 28 so that the pan may 60 be dropped or removed from the machine.

Likewise, to replace the pan the three notches 31 are placed in position beneath the holding arms 32 and the pan pushed upwardly until the ring 30 is above the holding arms 32, after 65 which the pan is turned sufficiently so that

these arms 32 will engage beneath the ring and hold the pan. At the upper end of the pan 29 is an inner apron 33 over which the paint coming down from the screen 21 will flow back into the pan.

70 In order to prevent an overflow of paint from the lower pan 29 up to the screen 21, should too much paint be fed to the machine, and to indicate to the operator when too much paint is being fed to the machine, I provide an overflow pipe 34 with its opening 35 suitably positioned in the wall of the pan 29. Thus when the overflow or accumulated paint in the lower pan 29 reaches the outlet 35 the operator will see it flowing from the pipe 34 and decrease the feed to the machine by controlling it from the feed pipe 20 or other feed source.

80 Referring now to the operation of the machine, the motor 8 is started, thereby rotating the spraying and pumping head including the pans 12 and cone 16. The paint is now fed to the pan 17 which because of its funnel shape feeds it through its central opening and down into the upper rotary spraying pan 12. By centrifugal force the paint dropping into the upper pan 12 is thrown or sprayed against the screen 21, the surplus paint in the upper pan 12 flowing downwardly through its central opening 12' and being thrown outwardly against the second pan 12 where by centrifugal force it is thrown outwardly against the screen. In this second or intermediate pan the surplus paint flows downwardly through the central opening and into the lower pan 12'. From this lower pan it is likewise thrown outwardly against the screen 21. By this centrifugal spraying action the fluid of the paint is forced through the screen 21 and either 90 flows down the outer face of the screen 21, or some of the fluid may be forced through sufficiently to drop down through the space inside the protective covering 25 and into the receiving annular pan 26. It will thus be 100 seen that as this paint is sprayed outwardly against the screen 21 a part of the fluid is forced through the screen, but the solids in the paint run down along the inner wall of the screen 21 carrying part of the fluid with it, for example such as is not forced through the screen and which the screen cannot take care of. So we have the inner face of this screen carrying the downward flow of solids 110 and adhering fluid.

115 It is to be noted that the spraying portion of the head is distributed so as to spray the paint substantially along the entire screen and a desired number of spraying elements and corresponding length of screen may be used, depending upon the output desired.

120 As the paint is thrown or sprayed from the revolving spray head it travels with a forward or tangential motion due to the centrifugal force, and upon impact with the 130

screen that portion of the paint not going through continues its forward motion running down on the inside of the screen in a circular path directed spirally downwardly through the action of the centrifugal force and gravity. I find that this action continually and automatically cleans the inside of the screen 21 and washes the coarse residue and adhering fluid down into the receiving pan 29. This pan 29 gradually fills up, with the heavier particles sinking to the bottom and the fluid matter floating to the top until it comes into contact with the open bottom cone pumping element 16. The paint is then in effect pumped upwardly by action of the revolving cone, that paint which is drawn up along the outer face of the cone being thrown outwardly along its surface against the screen, while a greater amount is carried up along the inner face of the cone until it reaches the top where it is thrown outwardly against the screen the same as from the spraying pans above. Of course, it will be apparent that the paint which is raised or pumped up from the lower pan 29 will also carry some of the solid particles with it and these, as before, are thrown outwardly against the screen to drop down into the lower receiving pan 29.

Thus we not only have the spraying action of the upper pans, but the surplus fluid, and the fluid adhering to the solids, is successively thrown or sprayed against the screen 21 until we have substantially a solid residue in the lower receiving pan 29, which when it becomes filled may be removed for cleaning.

As previously pointed out, if too much paint is being fed to the machine, that is more than the screen 21 can take care of, the overflow pipe 34 will give indication thereof to the operator so that the amount being fed may be reduced.

The fluid or strained paint which has been separated from the solids and flows into the annular receiving pan 26, continually flows therefrom through its outlet 27.

Thus we have a continual rotary spraying separating action of the machine, whereby the solids are separated from the fluid and such solid residue accumulated for removal.

To clean the various parts or secure access to the interior, the various elements may be removed from the machine or from their operative position and readily replaced.

In the use of the machine it may be suspended from the ring 10 at the top of the machine and when the lower or receiving pan 29 is filled it may be readily removed, cleaned and replaced. Or the machine may be set on the floor by letting it rest on the lower pan and then when this pan is filled the upper part of the machine, that is all the elements except the pan 29, lifted and either suspended off the floor or set over to one side by resting

upon the feet 28, which as previously stated extend beneath the cone 16 so as to prevent damage thereto.

What I claim as new and desire to secure by United States Letters Patent is:—

1. A rotary spraying fluid and solids separator machine of the character described comprising a spraying element rotatable on a vertical axis, a screen surrounding said element against which the material received by the element is forcibly thrown by centrifugal force by rotation of the element to screen the material, a receptacle for receiving surplus material not passing through the screen, and a rotatable cone shaped device engaged by the surplus material for raising such material and again spraying it against the screen by centrifugal force.

2. A rotary spraying fluid and solids separator machine of the character described comprising a vertical rotatable shaft, a plurality of spraying receiving pans carried by said shaft and having openings therein whereby surplus fluid fed to the pans will flow downwardly from pan to pan, a circular screen positioned around said pans to receive the material thrown outwardly from said pan to strain the same and separate the fluid from any solid, a receptacle beneath said screen and spraying pans to receive unscreened surplus material, a rotary lifting device carried by said shaft beneath the spraying pans and extending down into the receptacle to raise the surplus material therein, and means for spraying the raised surplus material against the screen.

3. A rotary spraying separator machine of the character described including combined pumping and spraying cone rotatable on a vertical axis, a material receiving pan into which said cone extends for contact with the material whereby the material is raised by rotation of the cone and spraying tangentially thereby, and a screen surrounding said cone against which the material is sprayed when leaving the cone.

4. A rotary spraying fluid and solid separator machine of the character described comprising a spraying element rotatable on a vertical axis, a screen surrounding said element, means for supplying material to said spraying element to be thrown against said screen, means for receiving material passing through the screen, a lower inside receptacle for receiving material not passing through said screen, and means for continuously removing material from the top of said receptacle and supplying it to the spraying element for further spraying against said screen.

5. A rotary spraying fluid and solid separator machine of the character described comprising a spraying element rotatable on a vertical axis, a screen surrounding said element, means for supplying material to said

- spraying element to be thrown against said screen, means for receiving material passing through the screen, a lower inside receptacle for receiving material not passing through said screen, and means utilizing and forming a part of the spraying element for withdrawing material from said inside receptacle for further spraying against the screen.
5. A rotary spraying fluid and solids separator machine of the character described comprising a spraying element rotatable on a vertical axis, a screen surrounding said element against which the material received by the element is forcibly thrown by centrifugal force by rotation of the element to screen the material, an annular pan surrounding the screen for receiving the material passing through the screen, a receptacle inside but below the screen for receiving the material not passed through the screen, and means for raising the material from the receptacle and spraying it against said screen by centrifugal force, said latter raising and spraying action being a continuing operation.
10. A rotary spraying fluid and solids separator machine of the character described comprising a spraying element rotatable on a vertical axis, a screen surrounding said element against which the material received by the element is forcibly thrown by centrifugal force by rotation of the element to screen the material, an annular pan surrounding the screen for receiving the material passing through the screen, a receptacle inside but below the screen for receiving the material not passed through the screen, and means for raising the material from the receptacle and spraying it against said screen by centrifugal force, said latter raising and spraying action being a continuing operation.
15. A rotary spraying fluid and solids separator machine of the character described comprising a spraying element rotatable on a vertical axis, a screen surrounding said element against which the material received by the element is forcibly thrown by centrifugal force by rotation of the element to screen the material, an annular pan surrounding the screen for receiving the material passing through the screen, a receptacle inside but below the screen for receiving the material not passed through the screen, and means for raising the material from the receptacle and spraying it against said screen by centrifugal force, said latter raising and spraying action being a continuing operation.
20. A rotary spraying fluid and solids separator machine of the character described comprising a spraying element rotatable on a vertical axis, a screen surrounding said element against which the material received by the element is forcibly thrown by centrifugal force by rotation of the element to screen the material, an annular pan surrounding the screen for receiving the material passing through the screen, a receptacle inside but below the screen for receiving the material not passed through the screen, and means for raising the material from the receptacle and spraying it against said screen by centrifugal force, said latter raising and spraying action being a continuing operation.
25. In witness whereof, I hereunto subscribe my name this 24th day of November, 1925.

FREDERICK H. LUENSE.
